UNITED STATES PATENT OFFICE

2,339,655

LAMP SHADE

Samuel Sher, Chicago, Ill.

Application April 7, 1941, Serial No. 387,244

10 Claims. (Cl. 240—108)

My invention relates to an improved shade construction, and particularly to a novel construction and arrangement of frame, the covering material, and to an improved means for securing the said covering material to the frame.

The invention has among its objects the production of a shade of the kind described which is not only particularly attractive, but which may be conveniently, economically and satisfactorily manufactured.

A further object of the invention is to provide a new and novel frame construction which may be pre-built and to which the covering material may be readily, conveniently and durably secured.

A further object is the production of a shade of the kind described in which the covering material is made in the form of a seamless tube of knit or woven or elastic or semi-elastic material which may be readily stretched in position on the frame and in which the material, due to its nature, after stretching in applying, will remain taut and smooth without wrinkles.

A further object is the production of a frame provided with means for readily attaching the cover to the frame by means of one or more annular members which may be sprung into position and positively engaged in the frame.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawing, wherein like reference characters indicate like or corresponding parts:

Fig. 1 is an elevational view of a lamp shade structure embodying features of the invention, a portion of the shade construction being broken away to better illustrate the construction;

Fig. 2 is a perspective view of the shade frame with the cover removed;

Fig. 3 is a sectional view taken substantially on line 3—3 of Fig. 1;

Fig. 4 is an enlarged perspective view showing the details of one of the methods of attaching the shade to the frame;

Fig. 5 is a perspective view of the tubular fabric covering material; and

Fig. 6 is a view similar to a portion of Fig. 3, illustrating a slightly modified construction.

The invention as illustrated in a lamp shade construction consists of a unitary frame made up of top and bottom annular rings 1 and 2 rigidly

connected together by the rods 3, over which is arranged a tubular seamless cover, preferably knit or otherwise formed, so that it is substantially stretchable, whereby it may be stretched over the frame and, due to its inherent characteristics, draw or contract and maintain itself taut or tight on the frame.

The particular frame illustrated, as before mentioned, consists of top and bottom frame members suitably connected together, one or both of the frame members being shaped to suit but as shown only the bottom frame member, being of channel shape. The bottom frame member 2 as illustrated consists of a strip 4 of suitable material, preferably in the form of a metal strip, which is provided with spaced flanges 5 and 6. In the drawing the flanges are shown as extending outwardly, but as will be hereinafter described, they might be turned inwardly and the channeled member might be either at the top or bottom or both, only the bottom member, however, being shown in the form of a channel. As most clearly shown in Fig. 4 the flange 6 is provided with serrations providing prongs 7—7, etc., which may be bent down as hereinafter described when the cover is applied to the frame and to secure one end of the cover in place. In some instances both flanges might be serrated.

The cover 10, as shown in Fig. 5, is made in the form of a seamless knit or woven tube open at the two ends. At one end, as shown the bottom, the same is hemmed or folded over a securing ring 11, the edge end 12 being stitched to the adjacent body of the cover as indicated at 13 so that the ring is held in place on the cover. The ring 11 is of a size to fit in the channel of the frame member 2, it being possible to spring the same into place, and when so positioned will be held in place when the cover is drawn to the interior of the shade, as shown in Fig. 4, and at the same time holds the cover edge firmly in place. The cover is drawn through the shade and up over the frame member 1 and then the edge drawn back to the frame member 2 and moved inwardly, whereby it will be engaged by the prongs 7. If desired, a reinforcing strip 14 may be secured about the edge of the cover, although ordinarily this is not considered necessary. After the same is positioned, as shown in Fig. 4, the prongs 7 may be turned down or bent over as indicated in Fig. 3. After the cover has been applied to the frame, a tape or ornamental strip 15 may be applied at the top and likewise a strip 16 at the bottom, as shown in Fig. 1. While I have not illustrated a construction in which the flanges on a frame mem-

ber are turned inwardly instead of outwardly, such arrangement and application of the cover thereto is obvious from the disclosures made herein. Likewise, while I have referred to a seamless knit tubular cover, I wish to include any elastic or semi-elastic material which will be satisfactory.

The construction shown in Fig. 6 is very similar, except in this instance the channeled frame member 19-20 is not provided with a serrated flange. The cover at the ends of the tube 10, indicated at 18 in Fig. 6, is provided with the rings 21 which are secured in place by stitching the ends 22 as indicated at 23. This cover is applied substantially as previously described, except that the two rings 21 are sprung into place, thereby retaining the cover on the frame. Tape may be applied similar to tape 16 shown in Fig. 1.

As was previously mentioned, it is more or less immaterial which ring or frame member is channeled, or whether the flange of the channel extends inwardly or outwardly, but the preferred construction and arrangement are as shown in the figures of the drawing. The covering being of seamless, stretchable material in the form of a tube, may be readily applied to the frame, and owing to its inherent qualities or characteristics, will tend to contract and maintain itself taut on the frame, free from wrinkles or bulges. The cover may be knit or woven with an intermediate section of a reduced diameter like an hour glass, as indicated by the dotted lines in Fig. 5, where it is to be extended over a frame member of less diameter than that at the ends, and vice versa, or it may be knit in one, two or more sections. I have not shown in the drawing any support for mounting the covered frame on a fixture, it being understood that any suitable support may be employed, the same being generally attached to the top frame member at a plurality of points, but it may, in some instances, be attached to the lower frame member and be likewise constructed so that it may be applied to a desired lighting fixture.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In a lamp shade construction of the kind described and in combination, a top frame member and a bottom frame member and means for rigidly connecting the two together, one of said frame members consisting of a strip of metal flanged at the top and bottom, providing a channel, a cover of fabric constructed to provide a tubular body, said cover having one end of said tubular body disposed in said channel and secured against one flange thereof, with the body extending therefrom to the opposite frame member and over the same back to adjacent its first mentioned end and secured to the other flange of the channel member, said first mentioned cover end provided with a ring of a size to seat in the channel and lock the cover to the frame member in said nested relation.

2. In a lamp shade construction of the kind described, an annular top frame member and an annular bottom frame member and means for rigidly connecting the two together in spaced re-

lationship, the bottom frame member consisting of a strip of metal provided with outwardly extending flanges at the top and bottom edges, the top flange being serrated to provide a plurality of 5 bendable prongs, a fabric cover of tubular construction provided with a ring reinforcement at one end, the cover at said reinforcement being extended under the flange and upwardly within the frame to the top member, and thence drawn 10 thereover and down to the said lower frame member with the edge at the end brought down to the channel into engagement with the said prongs, the prongs piercing the material and bent over, whereby the last mentioned edge portion 15 of the cover at the exterior of the frame is securely anchored to the bottom frame member.

3. In a lamp shade construction of the kind described, an annular top frame member and an annular bottom frame member and means for 20 rigidly connecting the two together in spaced relationship, one frame member consisting of a strip of metal provided with extending flanges at the top and bottom edge thereof, one flange edge being serrated to provide a plurality of 25 bendable prongs, a seamless fabric cover of tubular construction provided with a ring reinforcement at one end, the ring and edge of said cover thereat being disposed to engage one flange, and the cover extended to the opposite frame 30 member, and over the same back and to the first mentioned frame member to engage the prongs on the channel, said prongs being bent to secure the pierced material to the frame member, whereby the edge portions of the ends of the cover are 35 securely anchored to the frame member.

4. In a lamp shade construction of the kind described and in combination, a frame consisting of top and bottom frame members rigidly secured together to provide a unitary structure, 40 one frame member consisting of a strip flanged at its edges and formed to provide an annular channeled ring in which the channel is positioned at the periphery thereof, a continuous tubular knitted cover enclosing said frame at the interior and 45 exterior thereof, the ends of said cover arranged in juxtaposition at the channeled frame member, one cover end provided with a ring reinforcement for securing the end within the channel, and means on one flange of said channeled ring 50 for engaging and securing the other end of the cover to the flanged frame member.

5. In a lamp shade construction of the kind described and in combination, a frame consisting of top and bottom frame members secured together to provide a unitary structure, one frame member consisting of a strip flanged at its edges and bent to provide an annular channeled ring, a continuous seamless tubular cover enclosing said frame at the interior and exterior thereof 60 to form the lining and outer surface portion of the shade, respectively, the ends of said cover arranged in juxtaposition at the channeled frame member, one cover end provided with a ring reinforcement secured against one flange of the 65 channel ring for securing the said end within the channel, and means for securing the other end of the cover to the other flange of the flanged frame member adjacent the other secured end portion of said cover.

6. In a lamp shade construction of the kind described and in combination, a frame consisting of top and bottom frame members secured together to provide a unitary structure, the bottom frame member consisting of a strip flanged at its 70 edges and formed to provide an annular chan-

neled ring, one flange provided with a plurality of prongs, a seamless tubular knit cover covering said frame at the interior and exterior thereof, the two open ends of said cover arranged in juxtaposition at the channeled bottom frame member, one cover end provided with a ring reinforcement disposed within the channel for securing the end to the bottom frame member, the other end of the cover being engaged with said prongs to secure said end to the flanged frame member.

7. In a lamp shade construction of the kind described and in combination, a frame consisting of top and bottom frame members secured together to provide a unitary structure, one frame member consisting of a metal strip flanged at its inner and outer edges and bent to provide an annular channeled ring, a seamless tubular cover of stretchable fabric covering said frame at the interior and exterior thereof, the ends of said cover disposed in juxtaposition at the channeled frame member, one cover end provided with a ring reinforcement in engagement with the outer flange for securing the end within the channel, the other cover end provided with a reinforcement about the end, the inner flange provided with prongs engaging the last mentioned cover end and reinforcement and securing the same to the frame member.

8. In a lamp shade construction of the kind described, a top frame member, a bottom frame member, means for securing said frame members together, a cover consisting of a longitudinally stretchable fabric tube, the ends of the tube being secured to one frame member with the intermediate portion extending over the other frame member and thence back to and around said one frame member, the said one frame member consisting of a strip provided with a flange on each edge providing a channel and the end of the fabric tube terminating substantially within the channel, tube securing means associated with

one of the flanges of the strip for securing one end of the tube to said flange, and a securing ring attached to the other end of the tube and nested in the channel adjacent the other flange for securing the other end of the tube upon said flange.

9. In a lamp shade construction of the kind described, an annular top frame member, an annular bottom frame member, one of said frame members having an outwardly projecting flange at each edge, means for connecting and rigidly securing said frame members together, a cover of tubular seamless fabric material, securing means associated with one of said flanges of said frame member for securing one end of the cover to said flange with the body portion of the cover extending over the other frame member and thence back to adjacent the first mentioned end of the cover, and a ring attached to the last mentioned end of the cover and acting to hold said end of the cover against the inner side of the other flange.

10. In a lamp shade construction of the kind described and in combination, a supporting frame comprising a top frame member, a bottom frame member and means for rigidly connecting the two together in spaced relation, said bottom frame member having outwardly directed flanges providing a laterally extending annular shaped channel therein, a tubular shaped longitudinally stretchable cover element, the ends of said tubular cover element being positioned in said channel with the intermediate portion extending around the frame, and separate securing means individual to each flange for releasably securing the respective ends of said cover element to the respective flanges of said frame member with the ends of the tubular cover element lying substantially within the channel.

SAMUEL SHER.
